CLAIM

The ornamental design for an imaging device, as shown and described.

DESCRIPTION

FIG. 1 is a perspective view of an imaging device; FIG. 2 is a front view of the imaging device as shown in FIG. 1; FIG. 3 is a rear view of the imaging device as shown in FIG. 1; FIG. 4 is a left view of the imaging device as shown in FIG. 1; FIG. 5 is a right view of the imaging device as shown in FIG. 1; FIG. 6 is a top view of the imaging device as shown in FIG. 1; FIG. 7 is a perspective view of the imaging device according to a second embodiment; FIG. 8 is a front view of the imaging device as shown in FIG. 7; FIG. 9 is a rear view of the imaging device as shown in FIG. 7; FIG. 10 is a left view of the imaging device as shown in FIG. 7; FIG. 11 is a right view of the imaging device as shown in FIG. 7; and, FIG. 12 is a top view of the imaging device as shown in FIG. 7.

The broken line showing of vents and venting stats on the right, left and rear surface panels of the imaging device are

(Continued)

elements of the imaging device that are depicted for illustrative purposes only and that form no part of the claimed design.
